UNITED STATES PATENT OFFICE.

CHRISTOPHER GEORGE BONEHILL, OF BELMONT ROW, BIRMINGHAM, COUNTY OF WARWICK, ENGLAND.

BREECH-LOADING FIRE-ARM.

SPECIFICATION forming part of Letters Patent No. 404,380, dated June 4, 1889.

Application filed June 29, 1888. Serial No. 278,519. (No model.) Patented in England May 29, 1888, No. 7,823.

To all whom it may concern:

Be it known that I, CHRISTOPHER GEORGE BONEHILL, gun-manufacturer, a subject of the Queen of Great Britain, residing at Belmont Row, Birmingham, in the county of Warwick, England, have invented certain new and useful Improvements in Breech-Loading Small-Arms, (for which I have applied for Letters Patent in Great Britain, dated May 29, 1888, and numbered 7,823;) and I do hereby declare the following to be a full, clear, and exact description of the invention, reference being had to the accompanying drawings, which form part of this specification.

This invention relates, principally, to hammer-intercepting bolts or means for preventing the accidental falling of the hammers of double guns on the arm being fired. Figure 1 represents, partly in longitudinal vertical section and partly in elevation, a breech-loading double gun provided with hammer-intercepting bolts, and also trigger-safety means whereby the hammers are prevented from being accidentally discharged both by the jar-off on the discharge of the arm and by the accidental pulling of the trigger. The said view represents the front of the head of one of the hammers or tumblers coming under one of the intercepting-bolts. Thus it will be seen that each hammer or tumbler has an intercepting-bolt of its own, which automatically places itself in front of its hammer, and is only removed therefrom by the pulling of that trigger by means of which it is operated. Fig. 2 represents in elevation a like view as Fig. 1. Fig. 3 represents, partly in end elevation and partly in section, an end view of the said arm, taken on the dotted lines A B, Fig. 1. Fig. 4 represents a front and end view of one of the intercepting-bolts, and Fig. 4^A is the other intercepting-bolt. Fig. 5 is a front and end view of one of the pushers, and Fig. 5^A the same of the other pusher. Fig. 6 represents upon an enlarged scale a diagrammatic view of the intercepting-bolts and pushers; and Fig. 7 shows a plan of the same, but with the hammers behind the said bolts.

a are the barrels. *b* is the body of the arm;

c, the break-off; and *d* is a rear extension of the said body part; and working transversely through the said rear extension, which comes immediately under the tang-strap of the arm, are two intercepting-bolts *e f*, whose acting or extended ends *e² f²* come in front of the respective heads *g²* of the hammers *g* when in their normal positions. These intercepting-bolts are operated by the upper ends of vertical pushers *h i* coming and acting against the inclines *e³ f³*, disposed on the under sides of the said intercepting-bolts. The lower under sides of the said pushers are inclined, against which the upwardly-extended fore parts *j² k²* of the trigger-blades of the triggers *j k* act on the said triggers being pulled, so as to turn upwardly the said fore parts on their joint-pin *l*. Thus the pulling of the triggers forces the fore parts of the trigger-blades *j² k²* upon the inclines *h² i²* of the pushers *h i*, thereby raising the said pushers, which respectively act upon the inclines *e³ f³* of the intercepting-bolts *e f*, thus causing the bolts to slide inwardly and in opposite directions and so take their protruding ends *e² f²* of the respective bolts from in front of the heads *g²* of the hammers *g*. The intercepting-bolts are automatically pressed home or into their intercepting positions by springs *m n*, whose free ends act upon the rears of the bolts.

It will be observed that the intercepting ends of the bolts are slightly rounded off on their front sides, so that the hammers on being cocked automatically force the bolts back, which then snap in front of the bolts, as represented in Figs. 2 and 3.

The trigger-safety consists of a single sliding limb *o*, with a V-shaped under part *o²* and fore part *o³*, which latter slides through a guide *p* and comes against the rear end of the locking-bolt *q*, so that on the lever *r* being turned aside for the breaking of the barrels the safety-limb *o* is pressed back by the rear action of the bolt *q*, as aforesaid.

o⁴ is a snug on the fore part *o³*, adapted to come above the rear and upward extensions of the trigger-blades, so as to prevent the said triggers from rising.

o⁵ is a vertical limb, with its upper end engaging with the safety-slide *s*, while the said

sliding limb is kept in its two positions by the free end t^2 of a spring t playing over inclined part o^2 . The limb slides upon the pin u , carried by a bracket upwardly directed from the 5 under strap of the arm.

- To fire the arm, press back the slides, when the limb o moves rearwardly, and with a snug o^3 out of the range of motion of the rear extension of the trigger-blades. The pulling of 10 either one or other of the triggers—as, for example, j —raises its fore part j^3 , which acts upon the pusher h , whose upper side impinges upon the incline e^3 of the intercepting-bolt e , thereby sliding inward the said bolt, and taking its intercepting and protruding end e^2 from in front of the hammer or tumbler of the barrel intended to be fired, thus allowing the said hammer or tumbler to fall and discharge the arm.
- 15 20 Should the concussion created in the arm remove the sear v from the bent of the other hammer or tumbler, then the said hammer or tumbler is intercepted by the bolt end f^2 of the bolt f coming in front of it.
- 25 Having thus described my invention, I claim as new and desire to secure by Letters Patent—
1. In a concealed-hammer gun, the combination, with the hammers thereof and the intercepting cross-bolts $e f$, arranged, respectively, side by side at the back of the breech-body part, of the pushers $h i$, formed with the inclines $h^2 i^2$, vertically movable below said bolts, and the triggers $j k$, upon which the pushers rest, substantially as described.
- 30

2. In a concealed-hammer gun, the combination, with the hammers and lock mechanism, of the transverse bolts $e f$, arranged side by side at the back of the breech-body and formed with the under side inclines $e^3 f^3$, engaged by vertically-movable pushers, and the 40 springs $m n$, impinging against the ends of said bolts, substantially as set forth.

3. In a concealed-hammer gun, the combination, with the rear body part d and hammers $g g$, of intercepting-bolts $e f$, arranged 45 at the back of the breech-body part, pushers $h i$, engaging with and located below said bolts and above the triggers, and the triggers $j^2 k^2 h^2$, as set forth.

4. In a concealed-hammer gun, the combination, with the hammers $g g$, the cross-bolts $e f$, arranged at the back of the body part and having inclines $e^3 f^3$, of the pushers $h i$, located below said cross-bolts and having inclines $h^2 i^2$, and the triggers $i k$, with fore 55 extensions $j^2 k^2$, bearing on said inclines, substantially as described.

In testimony that I claim the foregoing I have hereunto set my hand this 7th day of June, 1888.

CHRISTOPHER GEORGE BONEHILL.
